A. HERSKOVITZ.
INCANDESCENT MANTLE.
APPLICATION FILED NOV. 26, 1915.

1,192,782.

Patented July 25, 1916.

Inventor:
Abraham Herskovitz,

his Atty.

UNITED STATES PATENT OFFICE.

ABRAHAM HERSKOVITZ, OF CHICAGO, ILLINOIS, ASSIGNOR TO PEERLESS LIGHT COMPANY, OF CHICAGO, ILLINOIS, A CORPORATION OF ILLINOIS.

INCANDESCENT MANTLE.

1,192,782.

Specification of Letters Patent. Patented July 25, 1916.

Application filed November 26, 1915. Serial No. 63,363.

To all whom it may concern:

Be it known that I, ABRAHAM HERSKOVITZ, a citizen of the United States, and a resident of Chicago, county of Cook, and State of Illinois, have invented certain new and useful Improvements in Incandescent Mantles, of which the following is declared to be a full, clear, and exact description.

This invention relates to incandescent gas mantles and has a special reference to that class of mantles known as the "inverted" type, and its principal object is to provide improved self contained means for facilitating the handling of the fragile gas mantle and for temporarily supporting the mantle in a carton or wrapper out of contact with the side wall thereof, whereby danger of breakage during storage or shipment is eliminated. It is well-known that mantles are constructed of material which must be handled with great delicacy and care and it frequently happens that the mantle is injured when placing it in the carton or removing it therefrom. With my improved mantle supporting device such danger is practically removed. Furthermore with my improved holder, it is possible to readily detach the mantle from a burner after having been in use, and to replace it thereon, which is almost impossible to accomplish with mantles unprovided with a holder of the present type.

This invention consists therefore of the several novel features hereinafter set forth and claimed.

The invention is clearly illustrated in the drawing, accompanying this specification, in which:—

Figure 1, is a central, longitudinal section through a carton with an incandescent gas mantle, embodying a simple form of the present invention, contained therein; Fig. 2, is a perspective view of the mantle; and Fig. 3, is an end view looking in the direction of the arrow 3, in Fig. 2, with the gas mantle removed.

In the embodiment of the invention illustrated in said drawing, 10, designates a carton, comprising a cylindrical shell, 11, having a bottom portion 12, secured therein, and having a removable cap or top 13, upon its open upper end. The cap has a downturned annular flange adapted to extend over the upper edge of the cylindrical shell, 55 in accordance with the common well-known

practice, to hold the cap in place upon the shell.

The mantle is seen at 14, and may comprise the usual supporting ring 15, of fire clay or other suitable fire proof material, 60 and the gas mantle 16, secured thereto in the usual manner. The ring 15, is provided with the usual horizontal mantle supporting lugs 17, there being three in number, and having end portions that project inward over the top of the ring and other portions that project outward beyond the outer margin of the ring.

The mantle support 18, is permanently secured to the ring 15, and has a member 19, 70 by means of which the mantle may be handled, and which is arranged to rest upon the upper edge of the shell 11, of the carton, whenever the mantle is placed therein, to thereby removably support the mantle in 75 the carton and out of contact with the inner wall of the shell. In the preferred embodiment of the invention said member 19, is in the form of a ring of larger diameter than the mantle, and having a downturned flange 80 20, arranged to extend down over the upper edge portion of the cylindrical shell. Extending inward and radially from the ring portion 19, are lug engaging members 21, there being three in number, one for each 85 lug 17, of the mantle ring 15, and said lug engaging members are formed with tongues 22, 23, arranged to project down along the sides of said lugs 17, each lug engaging member having at least one tongue which is 90 bent underneath the lower side of the adjacent lug, as at 24, so as to securely fasten the support 18, to the mantle ring 15. Said tongues 22, 23, engage those portions of the lugs 17, which project beyond the outer side 95 of the mantle ring, so as not to interfere with the inner ends of said lugs which are employed for supporting the mantle upon gas burners of the ordinary type used in connection with inverted incandescent 100 mantles.

From the above it is perfectly evident that the incandescent mantle may be handled safely by taking hold of the support 18, and when inserted in the carton the gas mantle will be sustained from the upper edge portion of the carton by the support which rests thereon. By making the flange 20, of such diameter as to fit fairly tight upon the shell, lateral play of the gas man- 110

tle while in the carton, is prevented, so that it will not contact therewith, regardless of the position in which the carton is held. After the mantle has been inserted in the box, the cap 13, is placed on the shell, thereby inclosing the incandescent mantle. To remove the mantle, the cap is detached, whereupon the supporting portion 18, of the mantle may be grasped and the latter withdrawn from the shell. The mantle with its attached support 18 may then be attached to a gas burner in the usual manner with the inner ends of the lugs 17, resting in the mantle supporting members of the burner. The support 18, forms a handle like member for facilitating the handling of the fragile gas mantle and operates to hold the gas mantle out of contact with the inner wall of the carton, and variations in diameter of the gas mantle do not interfere with the operation of the support unless the diameter is made larger than that of the support.

More or less variation of the exact details of construction is possible without departing from the spirit of this invention, and I desire, therefore, not to limit myself to the exact construction shown and described, but intend in the following claims to point out all of the invention disclosed herein.

30 I claim as new and desire to secure by Letters Patent:

1. An incandescent mantle, comprising a gas mantle, a ring for suspending said gas mantle, and a ring-like support therefor, permanently secured to said ring and adapted to temporarily support the gas mantle and its ring in a carton; said support having a supporting member capable of resting on the edge of an open end of the carton and having an element engaging the side of the carton wall for preventing sidewise movement of the mantle while in the carton.

2. An incandescent mantle, comprising a gas mantle, a ring for suspending said gas mantle, and an annular supporting member

permanently secured to said ring, said supporting member being adapted to support the gas mantle and its ring in a carton, and having an annular, downturned flange arranged to bear against the side wall of the carton for preventing lateral play therein.

3. An incandescent mantle, comprising a gas mantle, a ring for suspending the same, a flanged annular supporting member, arranged to rest upon the open end of a carton containing the mantle, said supporting member having ring gripping tongues formed integral therewith for securing said supporting member to said ring.

4. Means for temporarily supporting incandescent gas mantles in cartons, comprising a ring portion having a downturned flange, and radial arms formed with lug engaging tongues for securing said ring portion to the mantle.

5. Means for temporarily supporting incandescent gas mantles in cartons, comprising a ring portion having a downturned annular flange, and radial lug engaging tongues for securing the ring portion to the mantle.

6. Means for temporarily supporting incandescent gas mantles in cartons, comprising a ring portion having a downturned flange along its outer edge and radially projecting lug engaging arms on its inner edge, said arms being formed with lug embracing tongues for securing the ring portion to the mantle.

7. Means for temporarily supporting incandescent gas mantles in cartons, comprising a ring portion formed with an annular downturned flange along its outer edge, a plurality of radial arms formed on the inner edge of the ring, each of said arms having a pair of downturned lug engaging tongues, at least one of each pair of tongues being bent to underlie the arm from which it projects, and hold a lug therebetween.

ABRAHAM HERSKOVITZ.
